INVENTOR
William E. Wacker:

BY

George D. Richards

ATTORNEY

UNITED STATES PATENT OFFICE

WILLIAM E. WACKER, OF NEWARK, NEW JERSEY, ASSIGNOR TO AUGUST GOERTZ & CO., INC., A CORPORATION OF NEW JERSEY

COSMETIC BOX

Application filed August 24, 1928. Serial No. 301,753.

The present invention relates, generally, to improvements in cosmetic boxes or vanity cases; and the invention has reference, more particularly, to a novel means for retaining a compact base in a vanity case or other holding means in such a manner that it is firmly secured therein and yet can be easily and quickly removed and replaced by a similar compact base.

10 This invention has for its principal object to provide a simple, inexpensive and easily and quickly manufactured construction whereby a compact base can be easily and quickly inserted in or removed from a vanity case or other holder; and to this end is provided a frame of sheet metal which defines an opening around whose edges is provided a flange which is concavely curved to form a recess into and out of which the 20 compact base can be easily pressed or snapped.

Another object of the invention is to provide a holding frame adapted for securing the compact base against rotatable displacement or shifting relative to the vanity case 25 in which it is used with attendant advantages also hereinafter set forth.

Various other objects and advantages of the invention will be obvious from the following particular description of a vanity box 30 embodying the invention or from an inspection of the accompanying drawings; and the invention also consists in certain new and useful features of construction and combinations of parts hereinafter set forth and claimed.

35 In the accompanying drawings there is shown for purposes of illustration one form of vanity box embodying the invention, in which:

Figure 1 is a plan view of an open vanity 40 case showing the interior;

Figures 2, 3 and 4 are, respectively, a plan view, a bottom plan view, and a side elevation view of a compact base retaining frame;

Figure 5 is a plan view of a compact base;

45 Figure 6 is a plan view of a compact in a base;

Figure 7 is a sectional view on an enlarged scale taken along the line 7—7 of Figure 1; and

50 Figure 8 is an enlarged fragmentary view

in section taken along the line 8—8 of Figure 1 showing details of the compact holding flange of the frame.

Similar characters of reference are employed in all of the hereinabove described views to indicate corresponding parts.

Illustrative of the principles of this invention I have shown, in Figures 1 to 8 inclusive, a simple form of cosmetic box or vanity case, comprising a pair of hingedly connected sections so arranged that one of said sections constitutes a cover 10 and the other a body 11 upon which the cover closes. In boxes or cases of this character, which are designed to serve the purpose of cosmetic boxes or vanity cases, it is desired to attach therein a compact of the well known type which comprises a base 12 of sheet metal of disc-like form and which may be of shallow saucer shape if desired, on which base is provided a filling 13 of cosmetic in cake or solid form; and the invention relates to a novel construction of cosmetic base retaining frame 14 which may be easily and quickly attached in and detached from the body section of box 10 or case, and into and out of which retaining frame the cosmetic base can be easily and quickly inserted or removed. Said cover section 10 and body section 11 are of sheet metal and, as shown, are preferably of polygonal shape having, respectively, flanges 15 and 16 which meet and register with each other when the box or case is closed. Said body section 11 may be concave on its inner face to conform to a saucer shaped compact base 12, when a base of such shape is utilized.

Said frame 14 is of polygonal outline corresponding to the shape of the body section, and has flange like sides 17 which fit within 90 and against the flanges 16 on said body section 11 whereby the frame is held in the latter by friction and yet can be easily removed and reinserted or replaced at will. The inner opening 18 of said frame 14 is preferably 95 circular and has a downwardly extending bezel 19 which at its lower edge carries a flange 20 which is in the form of a channel which faces inwardly. The diameter of said opening 18, at the bottom of the channel de- 100

fined by flange 20, is approximately equal to the outer diameter of said base 12, and at the respective edges of flange 20 the diameter is slightly less so that these edges will present a little resistance to the passage of said base 12 into the channel defined by flange 20 and likewise to its removal therefrom. There is enough give or spring in said frame 14, particularly at said bezel 19 and flange 20, to permit said base 12 to be snapped into and out of place to and from the channel of said flange 20. The edge of said base 12 is turned over inwardly to a little extent and serves to provide for smooth movement of said base 12 into or out of the channeled flange 20 of the frame 14, said turned edge also serving to hold or aid in holding the cosmetic cake 13 in place. When the base 12 is mounted in the flange 20 of the frame 14, and said frame 14 is mounted in the body section 11, then the bottom of said base 12 rests on the interior face of said body section 11, as shown in Figures 7 and 8, and the base is held thereby from displacement from the channeled flange 20 even when extreme pressure is applied as in rubbing the cosmetic cake 13 with a powder puff. The angular form of the body section 11 and frame 14 keeps the latter from rotational movement when a powder puff is rubbed around on the cosmetic cake and the frictional engagement of the base 12 in said flange 20 keeps said base from turning. The sections 10 and 11 and the frame 14 can be other than the hexagonal shape illustrated in the drawings, for example, they may be octagonal, triangular, square or round, in which latter case the frictional engagement of the frame edge flanges with the flange of the body section will keep the frame from turning. Said frame 14 has a notch 21 formed therein at one of its lateral edges to accommodate the riveted inner end of the catch stud 22 attached to said body section 11 at a point opposite the hinge connection with said cover section 10, the latter having a clasp 23 for fitting over said stud 22 to secure the case or box in the closed condition. Said notch 21 serves also for the insertion of a knife point or a pin or other pointed instrument for removing said frame 14 when desired, as for example, for the purpose of removing the compact and base 12 for replacement. Said cover section 10 is provided with a frame 24 which is somewhat similar to said frame 14 and which serves to hold a mirror 25 in place in said cover section. When the box or case is closed there is sufficient space between the compact cake 13 and said mirror 25 to hold a powder puff.

60 While I have described the use of said frames 14 and 24 as means for retaining a compact base and a mirror, respectively, it will be understood that devices other than compact bases or mirrors can be thus secured by these frames. For example, the frame 14

can hold a mirror, the frame 24 can retain a compact base, or either one can hold or retain a decorative medallion or ornamental disc or plate. Also the body section 11 can be in the form of an open frame, which consists of the flange like sides 17 and sufficient of the main body portion to retain said frame 14 and base 12 from passing through, in which case the bottom of said base 12 can be provided with a décoration which will be exposed through the opening left in the body.

70 It is also to be understood that said vanity case or box, the frames thereof and other parts, and said cosmetic compact base, any or all of them can be made of sheet metal, celluloid, or other suitable material; and also that the channel shaped flange 20 can extend from said bezel 19 in the opposite direction from that shown, and to be contained in the latter, with its channel, of course, facing toward the opening.

80 Having thus described my invention, I claim:

1. In a vanity case, in combination, a body section having a peripheral flange extending from one face thereof to define a casing interior and a frame having flange like sides adapted to fit within the flange of said body section, said frame having a central opening about which extends a channeled flange adapted to spring and yield to the reception or displacement of an article having the same general contour as the bottom of the channel of said channeled flange.

90 2. In a vanity case, in combination, a body section having a peripheral flange extending from one face thereof to define a casing interior; a frame having flange like sides adapted to fit with frictional engagement within and against the flange of said body section, said frame having a central opening, a channeled flange depending from the margins of said opening, and said channeled flange being adapted to spring and yield to the reception or displacement of an article having the same general contour as the bottom of the channel of said channeled flange.

100 3. In a vanity case, in combination, a body section having side flanges extending from one face thereof to define a casing interior; a frame having flange like sides adapted to fit between the flanges of said body section, and having a central opening about which extends a channeled flange adapted to spring and yield to receive an article having the same general contour as the bottom of said channel of said channeled flange; and a cosmetic compact including a base having a contour adapted to fit in said channel and between the edges thereof.

110 4. A frame for use in a vanity case and adapted to hold a cosmetic compact and base, or other article, and consisting of a main portion defining an opening, a bezel extending from and about said opening, and a chan-

nel shaped flange extending from said bezel, said channel shaped flange being thin and having sufficient give and springiness to admit the passage of an article, of the same general outline as that of the bottom of the channel defined by the flange into said channel past the edges of the latter.

5. A frame for use in a vanity case and adapted to hold a cosmetic compact and base, or other article, and consisting of a main portion defining an opening, and a channel shaped flange extending from and about said opening and being resilient and springy and thereby adapted to admit the passage of an 10 article past its edges and into the channel 15 thereof.

6. In combination with a section of a vanity case, a frame carried thereby adapted to hold a cosmetic compact and base, or other 20 article, and consisting of a main portion defining an opening, and a channel shaped flange extending from and about said opening, said flange being resilient and springy and thereby adapted to admit the passage of 25 an article past its edges and into the channel thereof.

In testimony, that I claim the invention set forth above I have hereunto set my hand this 21st day of August, 1928.

30 WILLIAM E. WACKER.
